UNITED STATES PATENT OFFICE.

ALBERT HAYES, OF SALT LAKE CITY, UTAH, ASSIGNOR, BY MESNE ASSIGNMENTS, TO THE NEW LIGHT HEAT & POWER CO., OF UTAH.

COMBINED GAS AND VAPOR BURNER.

SPECIFICATION forming part of Letters Patent No. 669,989, dated March 19, 1901.

Application filed November 6, 1900. Serial No. 35,650. (No model.)

To all whom it may concern:

Be it known that I, ALBERT HAYES, a citizen of the United States, residing at Salt Lake City, in the county of Salt Lake, State of Utah, have invented certain new and useful Improvements in a Combined Gas and Vapor Burner, of which the following is a description, reference being had to the accompanying drawings and to the figures of reference marked thereon.

My invention relates to devices for vaporizing and burning hydrocarbon oils, particularly the heavier or less volatile oils, such as kerosene, for the production of heat for lighting or other purposes, and has for its objects to produce a device adapted for attachment to a gas-supply pipe in which gas alone may be used, in which hydrocarbon oil may be vaporized and the vapor mixed with the gas to enrich it, and in which the oil-vapor alone, mixed with air, may be burned, the gas-supply in the latter case being used for the purpose of starting the vaporization by merely regulating the supply of gas and oil.

My invention consists in the means herein-after described by which these objects are attained.

In the drawings, Figure 1 is a vertical sectional view of my improved device. Figs. 2 and 3 are horizontal sectional views on lines *a a* and *b b* of Fig. 1, respectively.

The device by which the oil is vaporized and burned is in its general construction preferably the same as that shown and described in the application for Letters Patent filed by me on the 27th day of October, 1900, Serial No. 34,531, and comprises an oil-chamber 1, to which oil is supplied under pressure, a double chamber above the oil-chamber, comprising an outer tube 20 and an inner or mixing tube 21, into which oil from the oil-chamber 1 is discharged, an air-inlet 23 for admitting air to the mixing-tube, downtake-passage 24, preferably tubes, as shown, for delivering gas from the mixing-tube into the space surrounding the base of the mixing-tube, an obstruction 25 to deflect a portion of the gas from the mixing-tube into the downtake-passage, a burner above the double chamber, and air-inlet passages 16 for admitting air from below about the upper portion of the oil-chamber.

The oil-chamber 1, as in the application re-

ferred to, is provided at its upper end with a nozzle 2, having through it an outlet-opening 3, which is made conical toward its lower end to form a valve-seat 4, in which fits a needle-valve 5. The oil-chamber has in its bottom an inlet-opening 6, controlled by a valve 7. The valve-stems 8 and 9, which carry the valves 5 and 7, respectively, are operated to control the outlet and inlet openings by a key 10, having on its shaft, within the oil-chamber, means for moving the two valve-stems simultaneously.

Surrounding the upper portion of the oil-chamber is a tube 15. Between this tube and the upper portion of the oil-chamber are formed air-passages 16, preferably by arms 17 of the form shown in Fig. 3, preferably formed integral with the tube 15 and extending inward to the oil-chamber.

Above the arms 17 is placed a ring 19 of perforated metal, fitting between the tube 15 and the oil-chamber.

While the parts above described are preferably as in my application before referred to, it should be understood that my invention is not limited to the precise construction shown and described therein.

Exterior to the tube 15 and spaced a short distance from it is an outer tube 27. The two tubes are connected at their lower edges, as shown, by an imperforate ring 28.

The tube 15, instead of extending up to and joining the outer tube 20 of the double chamber, as in the construction shown in my application before referred to, terminates at a point slightly below the upper end of the oil-chamber. The double chamber is supported by the tube 27, the outer tube of the chamber being preferably made, as shown, of a size to fit within the upper end of tube 27.

Through the tube 27, preferably at a point near its lower edge, is formed a gas-inlet opening 29, and in this opening is secured the end of a connecting-pipe 30. In order to hold this pipe firmly in position, the tube 27 is preferably provided with a reinforcing-ring 31 of sufficient thickness to have screw-threads cut therein to receive the screw-threads formed on the end of the pipe. At its outer end the pipe 30 is provided with a coupling 32, by which it may be connected to a gas-service pipe 33. The pipe 34 may be the terminal of an ordinary gas-fixture. The

connecting-pipe 30 is made sufficiently strong and in its connection to the tube 27 sufficiently rigid to permit the whole device to be supported from the gas-fixture, in which case 5 the oil-supply tube 35 will be led along the gas-pipe from a suitable tank containing oil under pressure.

If the device is to be used as a table light, it should be provided with a suitable base, 10 and the gas may be supplied from any convenient fixture by a flexible tube, the oil being supplied from a tank on or beneath the table.

The device, as shown, being secured to a 15 gas-supply pipe and the gas turned on, the gas will pass through the pipe 31 into the space between the outer tube 27 and tube 15 and up through the mixing-tube 21 to the burner. Air will enter through the passages 20 16 and the air-inlet 23 and mix with the gas. A portion of the mixed gas and air will be deflected by the obstruction 25 into the down-take-passage and when ignited will be caused 25 to form a cone of flame by the draft of air from the passages 16 within the base of the mixing-tube. The main portion of the mixed gas and air will pass through the obstruction 25 to the burner, where it will be ignited and will heat the mantle to incandescence. The 30 gas passing through the cone of flame will be highly heated and will more readily mix with the air entering through the air-inlet and will heat the mantle more satisfactorily than in the burners in which the gas is not thus heated. As soon as the cone of flame is formed 35 the outlet-valve of the oil-chamber may be opened. The oil discharged is vaporized in its passage through the cone of flame and mixing with the air entering through the air-inlet 23 and with the gas will form very rich 40 gas, by which the mantle will be heated to a much more brilliant incandescence than could be secured without the addition of oil-vapor. When the vaporization of the oil is once begun, the gas-supply may be cut off and the 45 device run as a vapor-burner.

By closing the outlet-valve of the oil-chamber and regulating the gas-supply a low light 50 may be kept burning, as desired, it being necessary only when a stronger light is desired to turn on the gas for an instant and open the outlet-valve of the oil-chamber.

By thus combining in one device a gas and 55 vapor burner I provide a light which can be regulated between wide limits from the lowest light possible with a gas incandescent light to the most powerful light possible from a vapor-burner.

While my invention has been described as 60 a light, it should be understood that it may be used for general heating purposes, the article to be heated being placed above the burner in place of the mantle. The gas produced in the mixing-tube may, if desired, be 65 used in a gas-engine or for any purpose for which a gaseous compound of vapor and air, such as is there formed, may be adapted.

By the use of my device a gas-supply of inferior quality may be enriched by the addition of oil-vapor, so that a light of great 70 brilliance may be produced.

Having thus described my invention, what I claim as new, and desire to secure by Letters Patent, is—

1. A combined gas and vapor burner, comprising a mixing-tube, means for supplying a fixed combustible gas to the mixing-tube, means for forcing oil in a fine stream or spray into the mixing-tube, and means for maintaining a vaporizing-flame within the mixing-tube about the stream or spray of oil. 75

2. A combined gas and vapor burner, comprising a mixing-tube, means for supplying a fixed combustible gas to the mixing-tube, means for forcing oil in a fine stream or spray 85 into the mixing-tube, means for maintaining a vaporizing-flame within the mixing-tube about the stream or spray of oil, and means for mixing air with the gas and vapor.

3. A combined gas and vapor burner, comprising a mixing-tube, means for supplying a fixed combustible gas to the mixing-tube, means for forcing oil in a fine stream or spray into the mixing-tube, means for vaporizing the oil in the mixing-tube, means for mixing 95 air with the gas and vapor, and a burner separate from the mixing-tube arranged to receive the mixed gas, vapor and air therefrom. 90

4. A combined gas and vapor burner, comprising a mixing-tube, means for admitting 100 air to the mixing-tube, means for supplying a fixed combustible gas to the mixing-tube, means for forcing oil in a fine stream or spray into the mixing-tube, and a downtake-passage leading from the upper end of the mixing-tube to its base to maintain a vaporizing-flame within the mixing-tube. 105

5. A combined gas and vapor burner, comprising a mixing-tube, means for supplying a fixed combustible gas to the mixing-tube, 110 means for forcing oil in a fine stream or spray into the mixing-tube, means for maintaining a vaporizing-flame about the entrance of the mixing-tube, and means for forcing the flame into the mixing-tube into the path of the 115 stream or spray of oil.

6. A combined gas and vapor burner, comprising a mixing-tube, means for supplying a fixed combustible gas to the mixing-tube, 120 means for forcing oil in a fine stream or spray into the mixing-tube, means for maintaining a vaporizing-flame about the entrance of the mixing-tube, means for forcing the flame into the mixing-tube into the path of the stream or spray of oil, and means for mixing air with 125 the gas and vapor.

7. A combined gas and vapor burner, comprising a mixing-tube, means for supplying a fixed combustible gas to the mixing-tube, means for forcing oil in a fine stream or spray 130 into the mixing-tube, means for maintaining a vaporizing-flame about the entrance of the mixing-tube, means for forcing the flame into the mixing-tube into the path of the stream

or spray of oil, means for mixing air with the gas and vapor, and a burner separate from the mixing-tube, arranged to receive the mixed gas, vapor and air therefrom.

5 8. A combined gas and vapor burner, comprising a mixing-tube having an air-inlet, means for supplying a fixed combustible gas to the mixing-tube, means for forcing oil in a fine stream or spray into the mixing-tube, means for maintaining a vaporizing-flame about the entrance of the mixing-tube from the mixture formed in the mixing-tube, and means for forcing the flame into the mixing-tube into the path of the stream or spray 15 of oil.

9. In a combined gas and vapor burner, the combination with an oil-chamber containing oil under pressure and having an outlet, of a mixing-tube in line with the outlet, and means 20 for admitting air into the mixing-tube, means for delivering a portion of the mixture formed in the mixing-tube into the space below its base to maintain a vaporizing-flame, means for forcing the flame into the mixing-tube 25 into the path of the oil discharged from the outlet, and means for supplying a fixed combustible gas to the space below the base of the mixing-tube.

10. In a combined gas and vapor burner, the combination with an oil-chamber containing oil under pressure and having an outlet, of a mixing-tube in line with the outlet, and means for admitting air into the mixing-tube, means for delivering a portion of the mixture 35 formed in the mixing-tube into the space below its base to maintain a vaporizing-flame, means for forcing the flame into the mixing-tube into the path of the oil discharged from the outlet, and means for supplying a fixed combustible gas to the space below the base of the mixing-tube, and a burner separate from the mixing-tube arranged to receive the mixed 40 gas, vapor, and air therefrom.

11. In a combined gas and vapor burner, the combination with a chamber containing oil under pressure having a valve-controlled outlet, of a mixing-tube above and in line with the outlet, means for maintaining a vaporizing-flame about the base of the mixing-tube, means for causing the flame to assume 50 a substantially conical form within the mixing-tube with the apex of the cone in the path of the oil discharged from the outlet, and means for supplying a fixed combustible gas about the base of the mixing-tube.

12. In a combined gas and vapor burner, the combination with a chamber containing oil under pressure having a valve-controlled outlet, of a mixing-tube above and in line 60 with the outlet, means for maintaining a vaporizing-flame about the base of the mixing-tube, means for causing the flame to assume a substantially conical form within the mixing-tube with the apex of the cone in the path of the oil discharged from the outlet, means 65 for supplying a fixed combustible gas about the base of the mixing-tube, and means for

admitting air to the mixing-tube above the flame.

13. In a combined gas and vapor burner, 70 the combination with a chamber containing oil under pressure having a valve-controlled outlet, of a mixing-tube above and in line with the outlet, means for maintaining a vaporizing-flame about the base of the mixing-tube, air-passages arranged about the upper portion of the oil-chamber to deliver an upward current of air to the vaporizing-flame to force the flame to assume a substantially 75 conical form within the mixing-tube, a gas-chamber arranged about the upper portion of the oil-chamber outside the air-passages and communicating with the space about the base of the mixing-tube, and means for supplying gas to the gas-chamber. 80

14. In a combined gas and vapor burner, the combination with a chamber containing oil under pressure having a valve-controlled outlet, of a mixing-tube above and in line with the outlet, means for maintaining a vaporizing-flame about the base of the mixing-tube, air-passages arranged about the upper portion of the oil-chamber to deliver an upward current of air to the vaporizing-flame to force the flame to assume a substantially 90 conical form within the mixing-tube, a gas-chamber arranged about the upper portion of the oil-chamber outside the air-passages, and communicating with the space about the base of the mixing-tube, means for supplying gas 95 to the gas-chamber, and means for admitting air to the mixing-tube above the flame.

15. A combined gas and vapor burner, comprising a double chamber, having an inner or mixing tube and an outer tube, means for admitting air to the mixing-tube, a down-take-passage between the mixing-tube and outer tube, an obstruction in the outer tube above the end of the mixing-tube, a burner above the obstruction, means for supplying 105 gas to the mixing-tube, and means for forcing oil under pressure into the mixing-tube. 110

16. In a combined gas and vapor burner, the combination of an oil-chamber having a valve-controlled outlet at its upper end, of a 115 tube surrounding the upper portion of the oil-chamber, air-inlet passages between the tube and the oil-chamber, an outer tube surrounding said tube and connected thereto at its lower end, a gas-inlet for admitting air into 120 the space between the two tubes, a double chamber above the oil-chamber comprising an inner or mixing tube, and an outer tube, means for admitting air into the mixing-tube, a downtake-passage for delivering a portion 125 of the mixture formed in the mixing-tube to the base of the mixing-tube, and an obstruction above the mixing-tube.

In testimony whereof I affix my signature in presence of two witnesses.

ALBERT HAYES.
